INCLOSED FUSED SWITCH

Filed July 18, 1927

2 Sheets-Sheet 2

UNITED STATES PATENT OFFICE.

JOSEPH SACHS, OF WEST HARTFORD, CONNECTICUT.

INCLOSED FUSED SWITCH.

Application filed July 18, 1927. Serial No. 206,733.

The invention relates particularly to an inclosed fused switch having the fuse contacts and the switch parts arranged to be respectively accessible and inaccessible through an opening in the front cover or wall of the inclosing cabinet, having a fuse cover for closing the opening in the front wall and normally preventing access to the fuse contacts, and having a movable element arranged in 10 interlocking relationship with the fuse cover and with the switch operating handle.

An inclosed fused switch embodying the present invention is in some respects similar to that disclosed in my copending application for Inclosed fused switches, Serial No. 709,943 filed April 30, 1924. The said application discloses an inclosed fused switch having an openable front cover with an opening therein and a laterally movable auxiliary cover for the opening having two positions, one being a normal closed position, and the other being a laterally projecting position. In its normal position the auxiliary cover is directly obstructed against lateral movement 25 by means of the switch handle and in its projecting position the auxiliary cover directly obstructs the switch handle against movement to switch closing position.

The result of this construction is that the auxiliary cover must move laterally through a distance sufficient to permit the said cover to entirely expose the opening in the main cover. In some cases, particularly for switches of the larger sizes, this extensive 35 lateral movement of the cover is objectionable as it subjects the projecting portion thereof to possible injury and as it prevents the close horizontal spacing of two or more switches.

One of the objects of the present invention, 40 is to provide an improved inclosed fused switch having an interlocking element separate from the auxiliary cover and having a relatively small range of movement to lock and unlock the cover, the actual opening of 45 the cover being effected by a movement-supplemental to the movement of the interlocking element.

A further object of the invention is to provide certain improved structural features 50 whereby the foregoing major advantage and other secondary advantages are obtained.

In the accompanying drawings I have shown the preferred embodiment of the invention, together with a variation thereof as 55 to certain details, but it will be understood that the drawings are intended for illustra-

tive purposes only and are not to be construed as defining or limiting the scope of the invention, the claims forming a part of this specification being relied upon for that purpose. 60

Of the drawings:

Fig. 1 is a front view of an inclosed fuse switch embodying the invention.

Fig. 2 is a fragmentary side view of the switch shown in Fig. 1.

Fig. 3 is a bottom view of the switch shown in Fig. 1, the rear part being shown in elevation and the front part being shown in transverse section along the line 3—3 of Fig. 1.

Fig. 4 is a fragmentary sectional view taken 70 along the line 4—4 of Fig. 1.

Fig. 5 is a fragmentary view similar to Fig. 3 but showing the parts in different relative positions.

Fig. 6 is a detail view of the cover and of 75 the slide upon which the cover is mounted.

Fig. 7 is a sectional view taken along the line 7—7 of Fig. 6.

Figs. 8, 9 and 10 are front, side and bottom views respectively of the guide plate for the 80 cover and slide.

Figs. 11 and 12 are fragmentary views similar respectively to Figs. 8 and 10 but showing an alternate form of guide plate.

Fig. 13 is a fragmentary sectional view 85 somewhat similar to Fig. 5 but showing the alternate form of guide plate with an alternate form of auxiliary cover cooperating therewith. The location of the section is indicated by the line 13—13 of Fig. 11.

As concerns the details of the cabinet to which the invention may be applied, I do not narrowly limit myself but in order to clearly illustrate the invention I have shown an inclosing cabinet 1 of conventional form having 95 a back wall 2, side walls 3 and 4, top and bottom end walls 5 and 6, and a front wall 7. Ordinarily and preferably the front wall 7 is in the form of an openable cover pivoted at 8, 8 to one of the walls as for instance 100 the bottom end wall 6. The cover may be held in closed position by means of a latch 9. The front wall 7, whether constructed in the form of an openable cover or otherwise, has an opening such as 10 therein.

Mounted within the cabinet is a fused switch mechanism so arranged that the fuse contacts are accessible from the exterior of the cabinet through the opening 10 when the cover is closed and so arranged that the 110 switch parts are inaccessible through the said opening when the cover is closed. The details

of the fused switch mechanism may be widely varied and I do not limit myself to a fused switch mechanism of any particular form. However, for the purpose of clearly illustrating the invention I have shown a fused switch of the type disclosed in my copending application for Electric circuit controlling appliance, Serial No. 165,645 filed Feb. 3, 1927. The fused switch as shown comprises a 10 base 11 of insulating material which is so mounted within the cabinet as to close the opening 10 in the front cover. Carried by the base 11 at the front thereof are pairs of fuse receiving contacts such as 12, 12 these 15 contacts being accessible from the exterior of the cabinet through the opening 10.

The switch mechanism within the cabinet comprises stationary switch contacts 13 and 14 some of which may be electrically connected with the respective fuse contacts 12, 12. In addition to the stationary switch contacts 13 and 14 the switch comprises movable contacts 15 and 16 carried by rectilinearly movable insulating elements 17, 17.

25 I provide an operating means for the switch a mechanism which includes a handle on the exterior of the cabinet, this handle being adjacent one side wall of the cabinet, as for instance the side wall 4, and being 30 movable parallelly therewith. As illustrated there is a switch operating spindle 18 having a cranked portion 19 which extends into slots 20 formed in the insulating elements 17 of the switching members. The spindle 18 is mounted in bearing apertures in the side walls 3 and 4 of the cabinet and it terminates in a handle 21 movable, as already described parallelly with the side wall 4 of the cabinet. When the handle 21 is in the position shown by full 35 lines in Figs. 1 and 2 the switch is in closed position. When the handle is moved to the position shown by dotted lines shown in Fig. 3 the switch is in open position. Preferably a stop device 21' is provided for limiting the 40 movement of the handle 21 and for preventing lateral distortion of the said handle.

In order to normally close the opening 10 in the front wall of the cabinet so as to prevent access therethrough to the fuse contacts, there is provided an auxiliary cover 22 50 which is preferably pivotally mounted for movement about an axis parallel to the front wall or main cover 7. Preferably the auxiliary cover is movable about a pivotal axis 55 which is vertical but as to this I do not necessarily limit myself.

In accordance with one phase of the invention the auxiliary cover is not only pivotally mounted as described but it is also arranged 60 to be bodily movable, when closed, in a direction parallel with the front wall or cover. In one position the cover is locked so that it cannot be opened and in another position it is unlocked so that it can be opened at will. I provide an interlocking means which is addi-

tional to the auxiliary cover itself and which is interposed between the said cover and the switch operating device, the said means serving to prevent bodily movement of the cover out of its first said locked position when the operating device is in its switch closing position and the said means also serving to prevent movement of the switch operating device out of its switch opening position when the cover is in its second said unlocked position. 75

Preferably the interlocking means is in the form of a laterally movable slide on the main cover having a normal position in which it is directly obstructed by the switch handle when the latter is in switch closing position and having a laterally projecting position in which it directly obstructs the handle against switch closing movement. When a laterally movable slide is provided as preferred and when the auxiliary cover is movable about a 80 vertical axis as preferred, I do not necessarily provide for the bodily movement of the auxiliary cover as already referred to, but as illustrated provision is made for the said bodily movement of the auxiliary cover by connecting the said auxiliary cover directly with the slide. As shown in the drawings the auxiliary cover is represented at 22, this being in the form of a flat plate slightly larger than the opening 10 in the main cover. The interlocking device or slide is represented at 23 and preferably the cover 22 is directly pivoted to the slide 23 for movement about a vertical axis, hinges 24, 24 being provided for this purpose. The details of the cover and slide 85 are clearly shown in Figs. 6 and 7. Preferably the slide has forward offset portions 23^a and 23^b, having their front surfaces in the same plane as the front surface of the cover 90 95

22. For holding the auxiliary cover and the slide in place on the main cover and for guiding the lateral movement thereof of the latter I provide a flat guide plate 25 which is secured to the main cover, being spaced from the front thereof as clearly indicated in Fig. 3. The auxiliary cover and the slide fit within the space between the front of the main cover and the rear of the guide plate, being free for lateral movement. The guide plate 100 105 110 115 25 is provided with an opening 26 which registers with the opening 10 in the main cover but which is preferably somewhat larger. The auxiliary cover is normally behind the plane of the guide plate and upon being opened it moves through the said opening 26 in the guide plate.

As already stated the slide 23 has two positions, one of which has been referred to as a normal position and the other of which has been referred to as a laterally projecting position. When the slide is in its normal position as shown in Figs. 1 and 3 the auxiliary cover is located in part behind the guide plate 25 and the guide plate therefore prevents the 120 125 130

opening of the said cover. However, when the slide 23 is moved to its laterally projecting position as shown in Fig. 5 the auxiliary cover 22 is in register with the opening 26 and 5 is free to be opened outward through the said opening to the open position shown by dot-and-dash lines. The pivotal axis for the cover 22 is at the left that is, at the side opposite the projecting position of the slide 23. 10 It will therefore be clear from an inspection of Fig. 5 that when the cover 22 is open or partly open the main body of the cover directly engages the guide plate at the left hand edge 27 of the opening 26. Thus the cover 15 itself, when open, prevents movement of the slide to its normal position.

It will be observed that, when the slide 23 is in its normal position with the auxiliary cover locked in closed position as shown in 20 Figs. 1 and 3, it is obstructed by the switch operating handle 21 when the said handle is in its switch closing position. However, when the handle 21 is moved to its switch opening position as shown in dotted lines in 25 Fig. 3 the slide 23 can be moved toward the right to its laterally projecting position as shown in Fig. 5 in which position it directly obstructs the handle against switch closing movement. From the foregoing description 30 it is apparent that the auxiliary cover can be opened to provide access to the fuse contacts only when the switch is open and that the switch can be closed only when the cover 22 is closed and locked to prevent access to the 35 fuse contacts.

For convenience in moving the cover 22 there is provided a knob 22', which serves as a means for moving the slide and the cover to the unlocked position of the latter and as a 40 means for moving the cover about its hinged axis. Thus the cover can be opened by taking hold of the knob 22' and moving the cover first toward the left and then forward, and the cover can be closed by reverse of these 45 movements.

In order to definitely limit the movement of the slide 23 suitable stops are provided. Movement toward the left beyond its normal 50 position is prevented by a downward turned flange 28 at the right hand end. Movement toward the right beyond its proper projecting position is prevented by means of stop lugs 29 and 30 formed on the slide and on the guide plate respectively. The slide may be 55 provided with an extension 31 having a hole therein for a sealing wire and the flange of the main cover may have a similar hole at 31' so that if desired the slide may be sealed in its cover closing position.

60 Preferably in order to provide a more positive locking of the auxiliary cover in closed position the said cover is provided with oppositely projecting ears 32, 32 and the opening 26 in the guide plate is provided with oppositely extending notches 33, 33 with which the

ears 32, 32 are adapted to register when the cover is in its unlocked position. From an inspection of Fig. 1 it will be obvious that when the auxiliary cover is in its locked position the ears 32, 32 are behind portions 34, 70 34 of the guide plate thus making the locking of the cover more effective.

It will be observed that, in the absence of a special means for preventing it, it might be possible for the ears 32, 32 of the auxiliary 75 cover to lie on the outside of the portions 34, 34 of the guide plate instead of on the inside as shown. With the said ears 32, 32 on the outside a limited amount of movement of the cover and slide could be effected before the 80 main body of the cover is brought into firm engagement with the guide plate at 27. With rough usage it might be possible to so bend or distort the parts as to permit the slide to be moved far enough to free the handle 21. To 85 avoid this possibility I prefer to provide supplemental means for preventing any lateral movement of the cover and slide except when the cover is fully closed so that the ears 32, 32 will pass behind the portions 34, 34, of the 90 guide plate.

I have shown a supplemental means for this purpose consisting of rearward extending flanges 35, 35 formed on the ears 32, 32 and normally extending through notches 36, 36 in 95 the slide 23. The main cover is preferably provided with depressions 37, 37 to receive the said flanges 35, 35. From an inspection of Fig. 5 it will be apparent that the auxiliary cover and slide can be moved only when the 100 cover is in its completely closed position. If the cover is partly open so as to be in any position below that shown by full lines the flanges 35, 35 will interfere with the guide plate at the lefthand edges of the notches 32, 32. If 105 the cover is still further opened the main body of the cover will interfere with the guide plate at the lefthand edge 27 of the opening 26 as already described.

In Figs. 11 to 13 I have shown an alternate 110 construction wherein the flanges 35, 35 on the ears 32, 32 are omitted and wherein there are provided forward extending flanges 38, 38 on the guide plate at the top and bottom edges of the opening 26^a. An inspection of Fig. 13 115 shows that the cover and slide can be moved only when the cover is completely closed. If the cover 22^a is partly open as shown, the ears 27^a, 27^a on the cover will interfere with the flanges 38, 38 on the guide plate. If the 120 cover is further opened the cover itself will interfere with the guide plate at the lefthand edge 27 of the opening 26 as already described.

What I claim is:

1. In an inclosed fused switch, the combination of a cabinet having an opening in one wall thereof, fuse contacts and a switch within the cabinet respectively accessible and inaccessible through the said opening, an exten- 130

nally accessible operating device for the switch, a pivotally mounted cover for the said wall opening, the said cover when closed being also bodily movable in a direction parallel with the last said wall, locking means with which the said cover is engaged when in one closed position and from which it is disengaged when bodily moved to another position, and an interlocking means additional to the 10 said cover and interposed between the said cover and the switch operating device, the said means serving to prevent bodily movement of the cover out of its first said locked position when the operating device is in its 15 switch closing position and serving to prevent movement of the operating device out of its switch opening position when the cover is in its second said unlocked position.

2. In an inclosed fused switch, the combination of a cabinet having an opening in one wall thereof, fuse contacts and a switch within the cabinet respectively accessible and inaccessible through the said opening, an externally accessible operating device for the 25 switch, a cover for the said wall opening pivotally mounted for movement about an axis parallel with the plane of the said wall, the said cover when closed being also bodily movable in a direction parallel with the last said 30 plane, locking means with which the said cover is engaged when in one closed position and from which it is disengaged when bodily moved to another position, and an interlocking means additional to the said cover and 35 interposed between the said cover and the switch operating device, the said means serving to prevent bodily movement of the cover out of its first said locked position when the operating device is in its switch closing position and serving to prevent movement of the 40 operating device out of its switch opening position when the cover is in its second said unlocked position.

3. In an inclosed fused switch, the combination of a cabinet having an openable main cover with an opening therein, fuse contacts and a switch within the cabinet respectively accessible and inaccessible through the said opening when the cover is closed, an externally accessible operating device for the switch, an auxiliary cover for the main cover opening pivotally mounted for movement about an axis parallel with the plane of the main cover, the said auxiliary cover when 50 closed being also bodily movable in a direction parallel with the last said plane, locking means with which the said auxiliary cover is engaged when in one closed position and from which it is disengaged when bodily 55 moved to another position, and an interlocking means additional to the said auxiliary cover interposed between the said cover and the switch operating device, the said means serving to prevent bodily movement of the 60 cover out of its first said locked position when 65

the operating device is in its switch closing position and serving to prevent movement of the operating device out of its switch opening position when the cover is in its second said unlocked position.

4. In an inclosed fused switch, the combination of a cabinet having an openable main cover with an opening therein, fuse contacts and a switch within the cabinet respectively accessible and inaccessible through the said opening when the cover is closed, a switch operating handle independent of said main cover and externally accessible for movement to on and off position, a slide mounted on the main cover to permit lateral movement, the said slide having a normal position in which it is directly obstructed by the external switch handle when in switch closing position and having a laterally projecting position in which it directly obstructs the handle against switch closing movement, an auxiliary cover mounted on the slide and movable separately from the slide to cover or expose the opening in the main cover and thus prevent or permit access through the opening in the main cover to the fuse contacts within the cabinet, and means co-related with said main cover and auxiliary cover to engage the auxiliary cover and hold it in closed position when the slide is in its normal position and to disengage the auxiliary cover when the slide is in switch handle obstructing position, whereby access to said fuse contacts through the opening in the main cover may be obtained when the switch handle is in the off position and is prevented when the switch handle is in the on position.

5. In an inclosed fused switch, the combination of a cabinet having an openable main cover with an opening therein, fuse contacts and a switch within the cabinet respectively accessible and inaccessible through the said opening when the cover is closed, a switch operating handle adjacent one side wall of the cabinet and movable parallelly therewith, a laterally movable slide on the cover having a normal position in which it is directly obstructed by the handle when in switch closing position and having a laterally projecting position in which it directly obstructs the handle against switch closing movement, an auxiliary cover for the main cover opening pivotally mounted on the slide for movement about an axis parallel with the plane of the main cover, means mounted in fixed position on the main cover for engaging the auxiliary cover to hold it in closed position when the cover and the slide are in their normal positions, the said means being disengaged from the cover upon movement of the cover with the slide to the laterally projecting position of the latter, and means for preventing the movement of the slide from its laterally projecting position to its normal position when the auxiliary cover is open or partly open.

6. In an inclosed fused switch, the combination of a cabinet having an openable main cover with an opening therein, fuse contacts and a switch within the cabinet respectively accessible and inaccessible through the said opening when the cover is closed, a switch operating handle adjacent one side wall of the cabinet and movable parallelly therewith, a laterally movable slide on the cover having a flat guide plate spaced from the front of the main cover and having an opening registering with the cover opening, a laterally movable slide between the main cover and the guide plate having a normal position in which it is directly obstructed by the handle when in switch closing position and having a laterally projecting position in which it directly obstructs the handle against switch closing movement, an auxiliary cover for the main cover opening normally located behind the plane of the guide plate and pivotally openable through the guide plate opening when the slide is in its laterally projecting position, means serving when the cover is open to prevent movement of the slide from its laterally projecting position to its normal position, and locking means engaging the auxiliary cover to hold it in closed position when the slide is in its normal position, the said means being disengaged from the cover upon movement of the slide to its laterally projecting position.

7. In an inclosed fused switch, the combination of a cabinet having an openable main cover with an opening therein, fuse contacts and a switch within the cabinet respectively accessible and inaccessible through the said opening when the cover is closed, a switch operating handle adjacent one side wall of the cabinet and movable parallelly therewith, a laterally movable slide on the cover having a normal position in which it is directly obstructed by the handle when in switch closing position and having a laterally projecting position in which it directly obstructs the said handle against switch closing movement, an auxiliary cover for the main cover opening pivotally mounted on the slide for movement about an axis parallel with the plane of the main cover and perpendicular to the direction of slide movement, means mounted in fixed position on the main cover for engaging the auxiliary cover to hold it in closed position when the cover and the slide are in their normal positions, the said means being disengaged from the cover upon movement of cover with the slide to the laterally projecting position of the latter, and means for preventing the movement of the slide from its laterally projecting position to its normal position when the auxiliary cover is open or partly open.

8. In an inclosed fused switch, the combination of a cabinet having an openable main cover with an opening therein, fuse contacts and a switch within the cabinet respectively accessible and inaccessible through the said opening when the cover is closed, a switch operating handle adjacent one side wall of the cabinet and movable parallelly therewith, a flat guide plate spaced from the front of the main cover and having an opening registering with the cover opening, a laterally movable

slide between the main cover and the guide plate having a normal position in which it is directly obstructed by the handle when in switch closing position and having a laterally projecting position in which it directly obstructs the handle against switch closing movement, an auxiliary cover for the main cover opening normally located behind the plane of the guide plate and pivotally openable through the guide plate opening when the slide is in its laterally projecting position, means serving when the cover is open to prevent movement of the slide from its laterally projecting position to its normal position, and locking means engaging the auxiliary cover to hold it in closed position when the slide is in its normal position, the said means being disengaged from the cover upon movement of the slide to its laterally projecting position.

9. In an inclosed fused switch, the combination of a cabinet having an openable main cover with an opening therein, fuse contacts and a switch within the cabinet respectively accessible and inaccessible through the said opening when the cover is closed, a switch operating handle adjacent one side wall of the cabinet and movable parallelly therewith, a flat guide plate spaced from the front of the main cover and having an opening registering with the cover opening, a laterally movable slide between the main cover and the guide plate having a normal position in which it is directly obstructed by the handle when in switch closing position and having a laterally projecting position in which it directly obstructs the handle against switch closing movement, an auxiliary cover for the main cover opening normally located behind the plane of the guide plate and pivotally openable through the guide plate opening when the slide is in its laterally projecting position, the said auxiliary cover when open serving as means for preventing movement of the slide from its laterally projecting position to its normal position, and locking means engaging the auxiliary cover to hold it in closed position when the slide is in its normal position, the said means being disengaged from the cover upon movement of the slide to its laterally projecting position.

10. In an inclosed fused switch, the combination of a cabinet having an openable main cover with an opening therein, fuse contacts and a switch within the cabinet respectively accessible and inaccessible through the said opening when the cover is closed, a switch operating handle adjacent one side wall of the cabinet and movable parallelly therewith, a flat guide plate spaced from the front of the main cover and having an opening registering with the cover opening, a laterally movable

slide between the main cover and the guide plate having a normal position in which it is directly obstructed by the handle when in switch closing position and having a laterally projecting position in which it directly obstructs the handle against switch closing movement, interengaging stops on the guide plate and on the slide for preventing movement of the slide beyond its said laterally projecting position, an auxiliary cover for the main cover opening normally located behind the plane of the guide plate and pivotally openable through the guide plate opening when the slide is in its laterally projecting position and the said stops are in engagement, means serving when the cover is open to prevent movement of the slide from its laterally projecting position to its normal position, and locking means engaging the auxiliary cover to hold it in closed position when the slide is in its normal position, the said means being disengaged from the cover upon movement of the slide to its laterally projecting position.

11. In an inclosed fused switch, the combination of a cabinet having an openable main cover with an opening therein, fuse contacts and a switch within the cabinet respectively accessible and inaccessible through the said opening when the cover is closed, a switch operating handle adjacent the one side wall of the cabinet and movable parallelly therewith, a flat guide plate spaced from the front of the main cover and having an opening registering with the cover opening and provided with notches at its opposite sides, a laterally movable slide between the main cover and the guide plate having a normal position in which it is directly obstructed by the handle when in switch closing position and having a laterally projecting position in which it directly obstructs the handle against switch closing movement, an auxiliary cover for the main cover opening normally located behind the plane of the guide plate and pivotally openable through the guide plate opening when the slide is in its laterally projecting position, the said cover having oppositely positioned ears movable through the notches in the guide plate, means serving when the cover is open to prevent movement of the slide from its laterally projecting position to its normal position, and locking means engaging the said ears to hold the auxiliary cover in closed position when the slide is in its normal position, the said means being disengaged from the ears upon movement of the slide to its laterally projecting position.

12. In an inclosed fused switch, the combination of a cabinet having an openable main cover with an opening therein, fuse contacts and a switch within the cabinet respectively accessible and inaccessible through the said opening when the cover is closed, a switch operating handle adjacent one side wall of the cabinet and movable parallelly

therewith, a flat guide plate spaced from the front of the main cover and having an opening registering with the cover opening, a laterally movable slide between the main cover and the guide plate having a normal position in which it is directly obstructed by the handle when in switch closing position and having a laterally projecting position in which it directly obstructs the handle against switch closing movement, an auxiliary cover for the main cover opening pivoted to the slide and normally located behind the plane of the guide plate and openable through the guide plate opening when the slide is in its laterally projecting position, the said auxiliary cover normally engaging a part of the guide plate so as to be thereby held in closed position and being disengaged from the said part of the guide plate upon movement with the slide to the laterally projecting position of the latter, and means serving when the said auxiliary cover is open or partly open to prevent the movement of the slide and the cover from the laterally projecting position of the latter to the normal position.

13. In an inclosed fused switch, the combination of a cabinet having an openable main cover with an opening therein, fuse contacts and a switch within the cabinet respectively accessible and inaccessible through the said opening when the cover is closed, a switch operating handle adjacent one side wall of the cabinet and movable parallelly therewith, a flat guide plate spaced from the front of the main cover and having an opening registering with the cover opening, a laterally movable slide between the main cover and the guide plate having a normal position in which it is directly obstructed by the handle when in switch closing position and having a laterally projecting position in which it directly obstructs the handle against switch closing movement, and an auxiliary cover for the main cover opening pivoted to the slide and normally located behind the plane of the guide plate and openable through the guide plate opening when the slide is in its laterally projecting position, the said auxiliary cover normally engaging a part of the guide plate so as to be thereby held in closed position and being disengaged from the said part of the guide plate upon movement with the slide to the laterally projecting position of the latter and the said cover when open or partly open directly engaging the guide plate at one edge of the opening therein to prevent the movement of the slide and the cover from the laterally projecting position of the latter to the normal position.

14. In an inclosed fused switch, the combination of a cabinet having an openable main cover with an opening therein, fuse contacts and a switch within the cabinet respectively accessible and inaccessible through the said opening when the cover is closed, a switch

In testimony whereof I have hereunto set
my hand this 12th day of July, 1927.

JOSEPH SACHS.
